UNITED STATES PATENT OFFICE.

CHARLES NEELY, OF EBENSBURG, PENNSYLVANIA.

SHINGLE-CUTTING MACHINE.

1,092,381.

Specification of Letters Patent.

Patented Apr. 7, 1914.

Application filed January 30, 1914. Serial No. 815,524.

To all whom it may concern:

Be it known that I, CHARLES NEELY, a citizen of the United States, residing at Ebensburg, in the county of Cambria and State of Pennsylvania, have invented certain new and useful Improvements in Shingle-Cutting Machines, of which the following is a specification, reference being had to the accompanying drawings.

10 This invention relates to a shingle cutting device and more particularly to a device which is designed primarily for cutting asbestos shingles.

The invention has for one of its objects 15 to provide a cutting or trimming machine for the above purpose whereby the asbestos shingles may be easily and quickly cut without danger of breaking or mutilating the same so as to render them unfit for use.

20 A further object of the device is to provide a gage which may be easily and quickly set for cutting the shingles to a required size.

In its more specific aspect the invention 25 includes a movable lever provided with a knife or cutting blade, a stationary blade secured to the base upon which said lever is mounted, said blades being so related to each other that they do not contact in the operation of the device, and a spring connected to said lever and normally holding the same in its raised or open position.

The invention has for a further object to 30 produce a cutting device for asbestos shingles which may be manufactured at comparatively small cost, and is highly durable as well as efficient and reliable in practical operation.

With the above and other objects in view 35 as will become apparent as the description proceeds, the invention consists in certain constructions, combinations and arrangements of the parts that I shall hereinafter fully describe and claim.

For a full understanding of the invention, reference is to be had to the following 40 description and accompanying drawings, in which—

Figure 1 is a perspective view of a shingle cutting device illustrating the invention 45 in its preferred form. Fig. 2 is a detail transverse section showing the arrangement of the cutting blade carried by the lever with respect to the blade on the edge of the base. Fig. 3 is a section taken on the line 50 3—3 of Fig. 1. Fig. 4 is a detail section taken on the line 4—4 of Fig. 1.

Referring in detail to the drawing, 5 indicates a base which is adapted to be secured upon a bench or other support by means of the bolts 6 which extend through 55 transversely disposed bars or cleats 7 secured to the underside of said base. These cleats at one of their ends project beyond the adjacent longitudinal edge of the base and to the same the uprights 8 are secured. 60 Standards 9 are fixed upon the upper surface of the base at its opposite ends, said standards being arranged in line with the uprights 8. Spacing blocks 10 are disposed between these standards and the uprights 8 65 and are secured to the same by means of suitable bolts or screws indicated at 11.

To the longitudinal edge of the base 5 between the standards 9 a metal plate 12 is secured, the upper edge of said plate being 70 flush with the upper surface of the base 5. It will be noted that one of the posts or uprights 8 is shorter than the other and between this shorter upright and the associated standard 9 one end of a lever 13 is pivotally mounted upon the bolt 14 which connects said standard and upright. To the side of this lever which is opposed to the base 5 the metal cutting plate 15 is secured. The lower edge of this plate extends below 75 the lower face of the lever. It is to be particularly noted from reference to Fig. 2 of the drawing that the plates 12 and 15 are slightly spaced so that they will not contact with each other in the operation of the lever. 80 The lever 13 extends between the upright and standard at the opposite end of the base 5 and is provided with a suitable handle 16. One end of the coil spring 17 is secured to 85 the lever 13 and the other end of said spring is fixed to the spacing block 10, said spring being arranged between the upright 8 and standard 9 as clearly shown in Fig. 1.

To the upper edge of the lever 13 a plate 18 is secured. This plate is formed with 90 diverging arms 19 having notches in their upper ends to receive a truss rod 20. The opposite ends of this rod are suitably secured to the lever 13.

In connection with the cutting machine I 95 employ a gage device. This gage includes a longitudinally disposed plate 21 which is mounted upon the arms 22, said arms being of channel form in cross section and provided at one of their ends with flanges 23 100 which are notched as at 24 to receive screws or studs 25 fixed in the edge of the base 5.

Each of the arms 22 is provided with a longitudinal slot 26, and in these slots the bolts 27 are arranged. These bolts also extend through short longitudinal slots 28 in the 5 gage member 21. Wing nuts 29 are threaded upon the upper ends of said bolts whereby the plate 21 may be securely clamped in its adjusted position. Upon the upper surface of the base 5 at one end thereof a plate 10 30 is secured, said plate being provided with an upstanding flange 31 extending transversely across the base. It will be obvious that by means of this construction, the asbestos shingles may be readily cut to any 15 width, and for the purpose of determining its width, the upper surfaces of the arms 22 on one side of the slots 26 therein may be provided with graduations 32 with respect to which the plate 21 is adapted to be 20 adjusted.

Having above described the construction and arrangement of the several parts of my invention, its operation may be stated as follows: The spring 17 acts by its contractile 25 force to hold the lever 13 in an elevated position as shown in Fig. 1. The asbestos composition shingle is laid upon the base 5 with one of its edges in contact with the upstanding flange 21' which is formed upon 30 the inner edge of the plate 21, one end of said shingle being engaged with the flange 31 on the plate 30. The shingle projects over the metal plate 12 which is secured to the edge of the base and beneath the lever 35 13. The operator forces downwardly upon the handle 16 of the lever so that the knife edge of the cutting blade 16 is brought into contact with the projecting portion of the asbestos shingle and cuts through the same. 40 By spacing the cutting edge of the plate 15 from the plate 12 so that there is no sliding contact between the same when the lever is forced downwardly, liability of the edge of the asbestos shingle being broken or mutilated 45 so that it would be unfit for roofing purposes is obviated, and the plate 15 cuts cleanly through the shingle and leaves an unbroken edge. This will be better understood when it is stated that the asbestos shingles for the cutting of which my invention 50 is particularly designed are formed from a composition of asbestos and plastic material so that they are perfectly stiff or rigid and will not flex or yield when the knife 15 is 55 brought into engagement therewith.

From the foregoing description taken in connection with the accompanying drawings it is believed that the construction, operation and several advantages of the invention will be clearly and fully understood. 60 The device provides means whereby the asbestos shingles may be easily and quickly cut or trimmed and the roofing of the building thereby may be greatly facilitated. The invention may be produced at very small 65 manufacturing cost, and owing to its simplicity will be very strong and durable in practical use. While I have referred to the cutting device as being secured to a work bench it will be obvious that it may be 70 mounted upon a stand or other support and readily moved from place to place.

While I have shown and described the preferred construction and arrangement of the several elements employed, it will be 75 understood that the invention is susceptible of considerable modification therein, and I therefore reserve the privilege of resorting to all such legitimate changes as may be fairly embodied within the spirit and scope 80 of the invention as claimed.

What is claimed is:

In a cutting device of the character described, a base, uprights arranged at opposite ends of the base in spaced relation to 85 one of its longitudinal edges, standards mounted upon the base in opposed relation to said uprights, a lever pivotally mounted at one of its ends between the standard and upright on one end of the base, and extending 90 between the standard and upright at the opposite end of the base, a metal plate secured to the longitudinal edge of said base, a spring connected to said lever and yieldingly holding the same in an elevated 95 position, a cutting blade secured upon one side of said lever and in spaced relation to the plate on the base, so that said blade will not contact with said plate when the lever is lowered, a plate centrally secured upon the 100 lever and provided with upwardly extending diverging arms, and a truss rod engaged over the ends of said arms and fixed at its ends to said lever.

In testimony whereof I hereunto affix my 105 signature in the presence of two witnesses.

CHARLES NEELY.
